US00D613402S

(12) **United States Design Patent**
Roberts et al.

(10) **Patent No.:** US D613,402 S
(45) **Date of Patent:** ** Apr. 6, 2010

(54) **EYE VIEWING DEVICE**

(75) Inventors: **Chris R. Roberts**, Skaneateles, NY (US);
Steven R. Slawson, Camillus, NY (US);
Scott P. Gucciardi, Syracuse, NY (US);
Scott W. Osiecki, Skaneateles, NY (US);
Timothy R. Fitch, Syracuse, NY (US);
Ronald J. Kingston, Syracuse, NY (US)

(73) Assignee: **Welch Allyn, Inc.**, Skaneateles Falls, NY (US)

(**) Term: **14 Years**

(21) Appl. No.: **29/207,233**

(22) Filed: **Jun. 10, 2004**

(57) **CLAIM**

The ornamental design for an eye viewing device, as shown and described.

DESCRIPTION

FIG. 1 is a first perspective view of an eye viewing device, according to the invention;

FIG. 2 is a second perspective view of an eye viewing device according to the invention;

FIG. 3 is a first side elevation view of an eye viewing device according to the invention;

FIG. 4 is a second side elevation view of an eye viewing device according to the invention;

FIG. 5 is a front view of an eye viewing device according to the invention;

FIG. 6 is a rear view of an eye viewing device according to the invention;

FIG. 7 is a top view of an eye viewing device according to the invention; and,

FIG. 8 is a bottom view of an eye viewing device according to the invention.

The broken lines in FIGS. 1 through 6 and FIG. 8 are included for the purpose of illustrating a portion of the eye viewing device that forms no part of the claimed design.

1 Claim, 6 Drawing Sheets
